UNITED STATES PATENT OFFICE

AUGUST DABRASKY, OF WASHINGTON, DISTRICT OF COLUMBIA

METHOD AND MEANS FOR SUPPLYING CARTRIDGE BELTS TO A FEED MECHANISM

Application filed September 15, 1930. Serial No. 482,009.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

5 This invention relates to a method of and means for supplying cartridge belts to a feed mechanism.

An uninterrupted supply of ammunition for a machine gun may be obtained by attaching the ends of short belts or strips carrying the ammunition. The rate of travel of the belt to the gun is so rapid that the operator charged with the task of establishing the connections must not only be extremely 15 alert but his undivided attention is required when the gun is being fired. The task becomes more difficult when the gun is being continuously moved as in tracking aerial targets and where several guns are placed 20 side by side on a single mount the congestion complicates the proceedings.

The purpose of the present invention is to provide a system of supplying belts of ammunition which is so organized that one operator can remove the belts from their containers and attach them to the belts passing through a number of guns.

With the foregoing and other objects in view the invention resides in the novel arrangement and combination of parts and in the method of application hereinafter described and claimed it being understood that changes in the precise embodiment of the invention herein disclosed may be made 35 within the scope of what is claimed without departing from the spirit of the invention.

A practical embodiment of the invention is illustrated in the accompanying drawing, 40 wherein:

Fig. 1 is a view in side elevation of a series of belts connected together and in position to be conducted into a feed mechanism;

45 Fig. 2 is a sectional view on the line 2—2 of Fig. 1;

Fig. 3 is a longitudinal sectional view through a container in which is carried a belt of ammunition;

50 Fig. 4 is a plan view of Fig. 3.

Referring to the drawing by numerals of reference:

There is shown a base 5 which is the traversing carriage of a gun mount. On the base are upright standards 6 in which a 55 cradle 7 is supported through trunnions 8.

The cradle carries a plurality of guns 9 placed side by side and in a depending support 10 it also carries a feed mechanism 11 and a cartridge guide 12 for each of the 60 guns.

In a multiple gun mount, a frame 13 is placed on the base 5 and is provided with a trough or channelled compartment 14 for each gun to be supplied with ammunition. 65 The compartments extend in the same direction as the gun and projecting through the floor 15 of each of them are a plurality of spaced rollers 16 sloping towards the feed mechanism to form a gravity conveyor. 70

The ammunition is carried in flexible belts 17 which may be either of the fabric or the disintegrating metallic link construction, the latter type being preferred and illustrated as it gives a better performance with heavy 75 cartridges such as the 50 caliber and as its links 18 permit the connection of two belts by the mere insertion of a cartridge. The belts in folded form are placed one behind another in the compartment 14 and are 80 arranged in such a manner that the two ends 19 and 20 are available respectively for attachment to the preceding and the following belt.

In order to facilitate such disposition of 85 the belts the box 21 (Fig. 3) in which each of them is carried has a transverse partition 22 spaced from one end to form a chamber 23 capable of receiving one thickness of the belt. The box is closed by a cover 24 held by 90 a pin 25 inserted through the ends of the box.

The operation of placing a belt of ammunition in a compartment consists in placing the box in inverted position in the compartment with the end containing the 95 partition remote from the preceding belt. The pin 25 is then withdrawn and the box lifted clear of the belt. The belt resting on the cover 24 will remain in the compartment, the cover lying on the rollers 16 so that it is 100

free to advance along the compartment and approach the feed mechanism. The two ends 19 and 20 of the belt are in exposed position, the end 19 being on the uppermost fold and the end 20 extending from the lowermost fold a length approximately equal to the height of a folded belt so that it may be moved into position to permit attachment to the end 19 of a following belt.

10 In initially arranging the ammunition supply preparatory to firing the guns the belt units are transferred from their containers to the compartments and attached. While the convenient length of the compartments will depend on the general design of the gun mount and the organization of its various parts it should preferably be capable of receiving a number of belt units providing a total number of rounds that is sufficient without replenishment for the needs of the gun during the period that a target is in range. With aerial targets this time is considered as one minute and according to the rate of fire of present guns the available supply should be approximately 600 rounds. The time interval of firing either alone or when added to the time interval between targets will afford ample opportunity for a single operator to replenish the ammunition supply for four guns.

The end plate 26 of the compartments is provided with an aperture 27 through which the cover 24 will pass when the belt that is supporting has been removed therefrom.

35 I claim:

1. A method of supplying ammunition to gun feed mechanism which consists in placing belt units on carriers one behind another, attaching the adjacent ends of the belt units, 40 and advancing all of the belt units toward a feed mechanism.

2. A method of supplying ammunition to gun feed mechanism which consists in placing belt units one behind another, attaching 45 the adjacent ends of the belt units, and advancing all of the belt units toward a feed mechanism.

3. In apparatus for supplying ammunition to gun feed mechanism, a support 50 formed with a channel and having an apertured end plate, rollers in the floor of the support forming a gravity conveyor, carriers movable on the rollers and through the 55 aperture in the end plate of the support.

4. In apparatus for supplying ammunition to gun feed mechanism, a support 60 formed with a channel, rollers in the floor of the support forming a gravity conveyor, and carriers movable on the rollers.

5. A container for a cartridge belt comprising a box, a partition transversely of the box and positioned adjacent one of its ends, a cover for the box and movable therefrom, 65 and means passing through the walls of the

box and positioned on the outer side of the cover to hold the cover in place.

6. A container for a cartridge belt comprising a box, a partition transversely of the box and positioned adjacent one of its ends, a cover fitting within the box and movable therefrom, said cover adapted to support the belt when the box is inverted and removed and means for removably holding the cover in place.

7. In combination, a container having a common entrance and exit, a flexible element carrying the contents of the container and folded upon itself with the upper end portion turned over to extend across the folds and a removable closure for the container.

8. A method of presenting a series of ammunition belts to a gun feed mechanism which consists in folding each belt upon itself with one end turned over across the 85 folds and attaching the turned over end of one belt to the folded end of an adjoining belt.
